CONTAINER SEALING MACHINE

Wilhelm B. Bronander, Montclair, N. J.

Application February 1, 1941, Serial No. 376,939

17 Claims. (Cl. 216—29)

This invention relates to a machine for sealing packages and containers.

More particularly stated, the invention relates to a machine for applying a seal between a container and a closure, such for instance, as a seal for sealing the junction or adjoining parts of a tobacco box and the lid for the box. As is well known, such boxes must be sealed or the contents will dry out and will not be in suitable condition for use. At the present time packages of this type are entirely enclosed in a wrapper of suitable sealing material, but when the outer wrapper is opened the seal is broken.

Many tobacco boxes are provided with hinged lids or caps which have a fairly tight fit except around the hinges where air leakage occurs.

This invention has for its object to provide a machine for sealing the lids or closures of containers of the type specified, the machine being simple and practical in construction and the seal being so applied that it may be easily broken when the package is to be opened.

Further objects of the invention will appear from the following specification taken in connection with the drawings which form a part of this application, and in which

Fig. 1 is an elevational view partly in section of a machine constructed in accordance with the invention;

Fig. 2 is a sectional elevation view of the machine shown in Fig. 1, taken substantially on line 2—2 of Figs. 3 and 4, with the front plate removed and showing the driving connections for the various parts of the machine;

Fig. 3 is a vertical sectional elevation taken substantially on line 3—3 of Fig. 2;

Fig. 4 is a vertical sectional elevation taken substantially on line 4—4 of Fig. 1;

Fig. 5 is a detail elevational view illustrating the guiding means for the container strip;

Figs. 5A and 5B are plan and elevational views of the knife for cutting and slitting the strip;

Fig. 6 is a plan view of the structure shown in Fig. 5;

Fig. 7 is a vertical sectional elevation taken substantially on line 7—7 of Fig. 6, this view being on an enlarged scale;

Fig. 8 is an elevational view on an enlarged scale showing the means for folding the ends of the outer or top seal around the ends of the lid and container;

Fig. 9 is a vertical sectional elevation taken substantially on line 9—9 of Fig. 8;

Fig. 10 is an elevational view illustrating the means for applying the outer or front sealing

strip and tearing strip to the lid and container;

Fig. 11 is a view of the portion of the guiding means shown in Fig. 10, but illustrating the parts in the position before the cutting means and tearing strip control means has descended or moved to operative position;

Fig. 12 is a detail sectional elevation of the cutting knife;

Fig. 13 is a sectional view of the cutting knife taken at right angles to Fig. 12;

Fig. 14 is a plan view of a portion of the sealing strip showing the slits made therein by the cutting knife illustrated in Figs. 12 and 13;

Fig. 15 is an enlarged sectional elevation taken substantially on line 15—15 of Fig. 1 and illustrating the cutter for cutting the outer sealing strip;

Fig. 16 is a plan view of the outer sealing strip and the tearing strip;

Fig. 17 is a plan view of the sealing strip for the back of the lid and container;

Fig. 18 is an end elevation of the container showing the two sealing strips in the positions in which they are applied and before being secured and folded around the ends of the container;

Fig. 19 is a sectional elevation through the container, lid and sealing strips;

Fig. 20 is a rear elevation of the upper end of the container and lid with the sealing strip supplied thereto; and

Fig. 21 is a similar view of the back of the container and lid;

Fig. 22 is an elevational view showing a modified form of strip pressing mechanism;

Fig. 23 is a view taken at right angles to Fig. 22; and

Fig. 24 is a sectional view taken substantially on line 24—24 of Fig. 23.

The invention briefly described consists of a machine for carrying out the method of sealing the junction between the box lid or closure and the box or container by securing the sealing strip along one side and around the ends of the container and closure and securing a second sealing strip along the other side and around the ends of the container and closure and in over-lapping relation to the ends of the first strip.

By sealing the closure in the manner outlined the outer seal can be removed when the closure or lid is to be opened, leaving the inner seal which extends along the back of the container in position. This seal prevents air from leaking in around the hinge openings.

Further details of the invention will appear from the following specification.

Although one particular machine for carrying out the method has been illustrated in the drawings, it should be understood that applicant does not intend to limit himself to the particular details of the construction illustrated.

In the embodiment of the invention illustrated in the drawings the machine comprises a pair of side plates 30 and 31 which may be termed, respectively, the front and rear plates.

The boxes or cans C are fed through the machine by feeding members 32 mounted on a pair of conveyor chains 33 which are supported on sprocket wheels 34, 34 at one end of the machine and sprocket wheels 35 at the other end thereof.

The cans or boxes C are beaded at the bottom thereof, as shown at 36, and a channeled guideway 37 is provided in the guide bar 38 secured to the rear plate 31 for guiding the cans as they are fed by the feeding members 32. The front end portions of the cans or containers are supported throughout the major portion of their feeding movement on the upper edge 39 of the plate 30.

The cans C may be fed to the machine by a conveyor or, as shown in Fig. 1, may be mounted in a hopper 40 from which they are fed by gravity between the successive feeding members 32 as the conveyor chains and feeding members advance.

The sealing strip S applied across the ends and the bottom of the cans as they are fed through the machine is carried by a supply roll 45 mounted on a spindle 46 and led upwardly around a guide roll 47 and a grooved roll 48 to a position beneath the path of feeding movement of the cans. A grooved roll 49 is disposed above the path of movement of the cans and presses the cans downwardly against the upper surface of the sealing strip which is supplied with an adhesive so that as a can engages the strip the strip will adhere thereto. The rolls 48 and 49 are grooved to receive the bead on the can.

The conveyor chains are driven intermittently with a slight dwell between the movements thereof, the driving connections illustrated being as follows:

As shown particularly in Fig. 2, the shaft 50 is driven in any suitable manner as by a motor and is provided with a gear 51 which meshes with a gear 52 mounted on a shaft 53. The face of the gear 52 has secured thereto four equally spaced rollers 54 which coat with slots 55 of a Geneva wheel 56 which has a hub 58 mounted on the shaft 57. On the hub 58 are mounted the sprocket wheels 34, 34 which support the endless carriers or chains 33 on which the feeding members 32 are mounted.

It will be evident from the form of driving connections above described that the feeding members will operate intermittently. When the first can is fed through the machine the front end of the strip S is secured around the front edges of the can, as shown at the right in Fig. 1.

On the next intermittent feed the can moves to the position shown in Fig. 5 on an enlarged scale, in which position the strip S is severed and the rear end thereof is folded around the rear end portions of the can. This is accomplished in the following manner:

A block 60 is provided with a downwardly extending guide portion 61 slidably mounted in a guideway 62 and vertically reciprocatable in the following manner: The portion 61 has pivoted thereto at 63 a link 64 which is also pivoted to a pin 65 carried by an eccentric disk 66 rotatably mounted on shaft 67.

At the upper end of the block 60 there is clamped to the right hand side edge thereof a knife 70. The block 60 is then raised in a manner hereinafter described by the rotation of the eccentric disk 66 and the strip S will be severed by the knife 70. The knife 70 has two right angle blades forming a cross and the blade 71 forms slits in the strip, as shown in Fig. 17. The block 60 also carries at the upper left hand end thereof a triangular shaped presser 72 which is grooved to receive the bead on the can and has a resilient or cushion facing 73. This presser is designed to fit between the advance end of one can and the rear end of the can in front of said can and to press the ends of the sealing strip S against the ends of the can, as shown at the left in Fig. 5. This takes place as the block 60 is raised.

The shaft 67 is driven in the following manner: Shaft 53, as above stated, has mounted thereon a gear 52 which meshes with a gear 75 carried by a shaft 76. This gear 75 meshes with a gear 78 carried by a shaft 79.

The gear 78 meshes with a gear 81 carried by a shaft 82. Gear 81 also meshes with a gear 84 mounted on a shaft 85. Gear 84 also meshes with a gear 87 mounted on a shaft 88. The latter gear 87 meshes with a gear 89 mounted on a sleeve 90 and gear 89 drives a gear 91 mounted on a shaft 92. The gear 91 also meshes with a gear 93 carried by the shaft 67.

During the operation of the block 60 the can is held down by a bar 95 which is carried by arms 96 and 97 which may, if desired, be adjustably mounted. The bar 95 has a ledge 98 which, as shown particularly in Fig. 7, engages the upper end surface of the lid of the can and holds the can in position as the flexible elastic saddle 72 presses the sealing strip against the bottom adjoining portions of the lid and can.

The bar 95 also has extending longitudinally thereof a groove 99 in which is disposed a tearing strip T which is mounted on a supply spool 100. The strip extends downwardly passing through an eye 101 disposed at the end of an arm 102 secured at 103 to the bar 95. From the eye 101 the tearing strip T passes around a grooved roller 104, through the groove 99, over a grooved roller 105 disposed at the other end of the bar 95 and beneath a guiding member 106 which is also carried by the bar 95.

The sealing strip S' for sealing the top of the can and lid as the can is passed through the machine is carried by a supply roll 110 mounted on a lever 111 carried by a bracket 112, a second supply roll 113 being mounted on the other end of the lever.

The strip S' is carried downwardly over a grooved or channeled roller 114 carried by a bell crank lever 115 carried by a sleeve 115' mounted on a shaft 116. The other end of a bell crank lever has mounted thereon a grooved roller 117 formed of resilient material, such as rubber, and the strip S' extends around the roller 117 and is secured to the advance end of the can. It will be noted particularly from the showing in Fig. 10 that the tearing strip T is positioned beneath the sealing strip S'.

The sleeve 115' also has secured thereto a bell crank lever 120 which has connected to one end thereof a spring 121 fixed at 122 to the back plate of the machine.

The other end of the bell crank lever 120 is connected by a link 123 to an arm 124 mounted on a fixed pivot 125. The arm 124 carries a roller

126 which engages a cam 127 carried by the sleeve 90. As the cam is rotated the roller and arm 124 will be raised and the link 123 will cause the bell crank lever 120 to be swung in an anticlockwise direction against the tension of the spring 121, thus causing the bell crank lever 115 to be swung in a corresponding direction, raising the roller 117. When the roller 126 engages the low portion of the cam 127 the spring 121 will cause the bell crank levers to swing in a clockwise direction or from the position shown in Fig. 11 to the position shown in Fig. 10, and even further in a clockwise direction until the roller 117 engages the back of strip S' and faces the strip against the back of the container or can C. The can C is thus held firmly between rollers 117 and 117' as it is fed forwardly by the chain.

The sealing strip S' is pulled downwardly and a downward pull is exerted on the tearing strip T in the following manner:

As shown particularly in Fig. 4, a block 130 is slidably mounted on a plate 30 and a roller 131 is mounted on a stud carried by the block 130, the stud extending through a slot in the plate 30. The roller 131 engages a cam 132 mounted on the sleeve 90. Springs 133 exert a downward pull on the block 130 and maintain the roller 131 in engagement with the cam 132.

The block 130 has secured thereto and extending upwardly therefrom a bracket 135, the upper end 136 of which extends inwardly or toward the plate 30 to a position above the strip S' (see Fig. 11). The portion 136 carries a pair of downwardly extending blades or knives 137 and 138 which as the part 136 is moved downwardly in the manner herein described form longitudinal slits 139 in the sealing strip S'. This strip, as will be hereinafter described, is severed intermediate the ends of the slits 139 and these slits are disposed at the edges of the tearing strip T and facilitate the initial tearing operation.

The block 130 has pivoted thereon at 140 a bell crank lever 141 having a finger 142 at the upper end thereof adapted to move inwardly between the sealing strip S' and the tearing strip T, as shown in Fig. 11. The bell crank lever 141 has slidably mounted therein, as shown at 143, a pair of telescoping studs 144 and 145 which are spring pressed in opposite directions by means of a spring 146. These studs have heads 147 at the outer ends which engage vertical guides 148 and operate in the following manner as the block 130 is moved upwardly and downwardly.

When the cam 127 has caused the bell crank lever 115 to swing in an anticlockwise direction to the position shown in Fig. 11, the arm 136 will be disposed above the tearing strip S' and the bell crank lever 141 and finger 142 will be disposed in the dotted line position shown in Fig. 4. As the cam 132 permits the springs 133 to pull downwardly on the block 130 the friction between the heads 147 and the guides 148 will cause the bell crank lever 141 to swing in a clockwise direction, thus moving the finger 142 to the position shown in full lines in Fig. 4 or above the tearing strip T. This will cause the tearing strip to be pulled downwardly a greater distance than the downward pull exerted by the arm 136 on the sealing strip S'. As the arm 136 moves downwardly the sealing strip will be slit, as shown at 139 in Fig. 14.

After the foregoing operation has been completed, the block 130 will be raised again by the action of the cam 132 and the cans will move to the next position in which the strip S' and

the tearing strip will be severed in the manner about to be described. When the block moves upwardly under action of the cam 132 the lever 141 will swing outwardly, as shown in dotted lines in Fig. 4.

During this movement the strip S' will be engaged by rollers 150 and 151, the cans being supported on grooved rollers 152 and 153.

The severing operation is accomplished by means of a knife blade 154 carried by an arm 155 having an angularly disposed portion 156 mounted on a shaft 157. Shaft 157 is driven by a spiral gear connection 158, 159 to shaft 85. The spiral gears are so timed that although the shaft 157 is rotated continuously the knife 154 will come into operation at the proper time in the sequence of operation of the machine to sever the strip S' and the tearing strip T. Since the tearing strip is pulled downwardly a greater distance than the strip S' the ends of the tearing strip will extend beyond the ends of the sealing strip S'.

After the severing operation just described has been completed the cans move to the next position of movement in which the final operation takes place, namely, the pressing of the ends of the upper sealing strip S' against the ends of the can and over the ends of the lower sealing strip S. This is accomplished in the following manner:

A block 160 is slidably mounted in guideways 161 and has pivoted thereto at 162 a link 163, the other end of which is pivoted to a pin 164 on a disk 165 mounted on the shaft 79.

The block has extending upwardly therefrom a bracket or post 166 and this bracket, as shown in Fig. 8, has a transverse block 167 at the upper end thereof, to the outer ends of which are pivoted at 168 a pair of lever arms 169. The arms 169 have clamped thereto by clamping members 170 the ends of a flexible strip of material 171.

The lever arms 169 are normally swung on their pivots 168 to positions in which the lower ends are outwardly disposed and the upper ends are inwardly disposed, this being accomplished by means of springs 172, the outer ends of which are secured to the upper ends of the arms 170 and the inner ends of which are secured to the bracket 165 and 173.

When the can is disposed beneath the transverse block 167 at the upper end of the arm 166 and beneath the flexible strip 171, the block 160 will be lowered causing the strip 171 to engage the sealing strip S' and to press the sealing strip tightly against the junction between the lid of the can and the can. Moreover, during the downward movement of the block and strip 171 the lower ends of the levers 169 will be pulled inwardly, thus firmly pressing the ends of the sealing strip S' against the ends of the can. In this manner the sealing strip S' will be firmly secured in sealing position.

In Figs. 22-24 inclusive, there is illustrated a modified form of construction for folding and pressing the ends of the outer sealing strip S' around the ends of the can or container.

In this modification the presser carried by the vertically reciprocatable slide 160' is simplified. The bracket 167' at the top of the slide has secured thereto a pair of blocks 175 and 176, generally triangular in shape, and provided with a resilient cushion or facing 177 engageable with the ends of the severed strip S' for pressing said ends against and around the ends of the can and

cover and in overlapping relation to the ends of the inner strip S.

The block 160 is reciprocated in the same manner as the block 160 in the first form of the invention illustrated.

In the form of the invention illustrated in Figs. 22-24 inclusive, further means is provided for securing and sealing the ends of the sealing strips around the ends of the can and the can cover. From the pressers 175 and 176 and from the discharge end of the feed conveyor the cans are pushed by a pair of arms 178, 179 carried by a sleeve 180 into radially disposed pockets 181, 182, 183, and 184 carried by a spider or hub 185 mounted on a shaft 186. The pockets are disposed 90° apart around the hub 185.

The sleeve 180 is mounted on a pin 187 slidably mounted in a slot 188 formed in the plate 31. Flanges 189 and 190 are mounted on the shaft or pin 187 on opposite sides of the plate 31.

The end of the pin or shaft 187 is mounted in a block 191 slidably mounted in one end of the lever 192 which is pivoted on the shaft 53 and has slidably mounted in its opposite end a block 193 having a pin 194 mounted on a disk 195 carried by the shaft 50.

As the shaft 50 rotates the lever 192 will be oscillated, thus causing the arms 178 and 179 to engage the rear upper ends of the cans as they are delivered by the can conveyor, whereby the cans will be successively pushed into the pocket 181-184 carried by the spider 185.

The shaft 186 and the spider 185 is driven in the following manner: Shaft 57 has mounted thereon a bevel gear 197 which meshes with a bevel gear 198 carried by a shaft 199. Shaft 199 has also secured thereto a gear 200 which meshes with a gear 201 which in turn meshes with a gear 202 mounted on the shaft 186. Since the shaft 57 is driven intermittently and controls the drive of the feed chain, the shaft 186 will also be rotated intermittently in synchronism with the drive of the chain which feeds the cans.

In the foregoing manner the cans are delivered successively to the pockets and each pocket has mounted in its outer end a spring strip 205 which engages the end of the can having the cover thereon and positions and holds the can in the pocket.

After a can has been fed into the pocket 181 viewing Fig. 23 the spider 185 is rotated through 90° to position the pocket 181 and the can therein in the position of the pocket 182 in Fig. 23. When the can reaches this position a final squeeze or pressure is applied to the ends of the outer strip S' and also to the ends of the inner strip S by means which will now be described.

This pressure is applied by arms 206 and 207 mounted on shafts 208 and 209 and provided on their free ends with resilient pads or cushions 210 shaped to fit around the ends of the can.

The shafts 208 and 209 are driven in the following manner: The eccentric 195 on the shaft 50 is enclosed by an eccentric strap 211 carried by a pitman rod 212, the other end of the rod being pivoted at 213 to an arm 214 secured to a shaft 215. The shaft 215 has mounted thereon a gear 216 which meshes with gears 217 and 218 carried by the shafts 208 and 209. Thus, the arms 206 and 207 will be oscillated, the operation being timed to swing the arms inwardly to engage the pads or cushions 210 with the outer ends of the strip S' and to press the strip firmly and securely against the outer ends of the can.

After the pressing operation just described has

been completed the spider 185 will be again rotated and after the second rotation after the pressing operation or, in other words, when the can has been moved through 180° from the 5 pressing position the can is discharged from the pocket by means of a plunger head 220 mounted on a plunger 221 secured to the carriage 222. The carriage 222 is reciprocated by the shaft 187.

Fig. 16 illustrates in plan view the upper sealing strip S' and it will be noted that the strip is slit at 139 to facilitate the initial tearing thereof by the tearing strip T.

Fig. 17 shows the lower sealing strip S with slits 175 at the ends. These slits facilitate opening of the lid or closure.

Fig. 18 is a somewhat diagrammatic view showing the positions of the two sealing strips S and S' and the tearing strip T before these strips are folded around the ends of the can and secured in position.

Fig. 19 is a cross sectional view through the can, lid and sealing strips, illustrating the completed positions of these various strips.

Operation

The operation of the machine may be briefly summarized as follows: The tearing strip S is led upwardly from the supply roll 45 and to a position below the path of movement of the cans 30 from the hopper 40. When the machine is started the front end of the strip S will be secured to the front edge portion of the first can. As the can moves to its next succeeding position the block 61 will be raised causing the flexible 35 elastic member 73 to press the sealing strip S firmly in position against the end portions of the can, the strip having been severed by the knife 72.

As the can passes from this position the tearing strip T is led over the can and to a position 40 beneath the upper sealing strip S'. The bell crank lever 115 will be swung in an anticlockwise direction raising the roller 117 to the position shown in Fig. 11. The arm 136 will be disposed above the strip S' and as the arm moves downwardly the finger 142 will move inwardly 45 to a position above the tearing strip T and the strip S' and the tearing strip will be pulled downwardly to the position shown in Fig. 10. During this downward pull the knives 137 and 138 will form slits 139 in the strip S'.

The can next moves to a position in which the knife 154 engages the strips S' and T and severs these strips leaving the ends of the strips extending downwardly and outwardly. From this 55 severing position the can moves to its last position in the machine in which the flexible member 171 and the pivoted arms 169 press the strip in sealing relation against the upper surface of the can and press the ends of the strip inwardly against the ends of the can and in overlapping relation to the ends of the lower strip S.

With the form of the invention illustrated in Figs. 22-24 inclusive, the cans are operated on by the pressing means 175 and 176 mounted at the upper end of the slide 160 and are thereafter 65 fed by the arms 178 and 179 into the pockets of the spider 185. The ends of the sealing strips are then given a further pressing operation by the arms 206 and 207 and the sealed cans are thereafter discharged from the pockets by the plunger head 220.

When the can is to be opened the tearing strip T is pulled, thus breaking the sealing strip S' which extends around the front of the can. The other sealing strip S, however, remains in seal-

ing position and covers the openings formed by the hinge at the back of the can, thus preventing air leakage. It will be understood that the remaining portion of the lid has a fairly tight seal when the lid is closed.

From the foregoing specification it will be seen that a simple, practical and efficient method and machine have been designed to seal cans in the manner specified.

Although certain specific embodiments of the invention and a particular machine have been described for carrying out the method, it will be understood that modifications and changes in the arrangement of the cooperating parts may be made and other mechanism may be utilized to carry out the method without departing from the spirit or scope of the invention as expressed in the following claims.

What I claim is:

1. Means for sealing closures to containers comprising means for feeding the containers and closures, means for applying a sealing strip to one side of the container bridging the adjacent portions of the container and closure, and means for applying a second sealing strip to the other side of the container, bridging the adjacent portions of the container and closure, the ends of the second strip overlapping the ends of the first strip.

2. Means for sealing closures to containers comprising means for feeding the containers and closures, means for applying a sealing strip to one side of the container bridging the adjacent portions of the container and closure, flexible means for pressing said strip firmly against the side and ends of the container and closure, means for applying a second sealing strip to the other side of the container, bridging the adjacent portions of the container and closure, and means for securing the firmly pressing said second strip against the side and ends of the container and closure, the ends of the second strip overlapping the ends of the first strip.

3. Means for sealing closures to containers comprising means for feeding the containers and closures, means for applying a sealing strip to one side of the container bridging the adjacent portions of the container and closure, means for applying a second sealing strip to the other side of the container, bridging the adjacent portions of the container and closure, the ends of the second strip overlapping the ends of the first strip, and means for positioning a tearing strip beneath said second sealing strip with an end of the tearing strip extending beyond an end of the second sealing strip.

4. Means for sealing closures to containers comprising means for feeding the containers and closures, means for applying a sealing strip to one side of the container bridging the adjacent portions of the container and closure, means for applying a second sealing strip to the other side of the container, bridging the adjacent portions of the container and closure, the ends of the second strip overlapping the ends of the first strip, means for positioning a tearing strip beneath said second sealing strip with an end of the tearing strip extending beyond an end of the second sealing strip, and means for slitting the end of the second sealing strip adjacent the projecting end of the tearing strip.

5. In a container sealing machine, means for feeding containers to be sealed, means for applying and securing a strip along one side and the ends of the container, and means for applying

and securing another strip to the other side and ends of the container, the ends of the second strip overlapping the ends of the first strip.

6. In a container sealing machine for sealing container closures to containers, means for feeding containers to be sealed, means for applying and securing a strip along one side and the ends of the container over the junction of the container and closure, and means for applying and securing another strip to the other side and ends of the container over the junction of the container and closure, the ends of the second strip overlapping the ends of the first strip.

7. In a container sealing machine, means for feeding containers to be sealed, means for securing a sealing strip along one side of the container, means for slitting said strip intermediate the longitudinal edges thereof, and means for severing the strip between the ends of the slits.

8. In a container sealing machine, means for feeding containers to be sealed, means for securing a sealing strip along one side of the container, means for slitting said strip intermediate the longitudinal edges thereof, means for severing the strip between the ends of the slits, and means for pressing the ends of the strip against the ends of the container.

9. In a container sealing machine, means for feeding containers to be sealed, means for securing a sealing strip along one side of the container, means for slitting said strip intermediate the longitudinal edges thereof, means for severing the strip between the ends of the slits, means for pressing the ends of the strip against the ends of the container, means for applying and securing a second sealing strip to the other side and ends of the container, means for applying a tearing strip beneath said second sealing strip, and means for slitting and severing the second strip, the slits being disposed at the ends of said strip adjacent the tearing strip edges.

10. In a container sealing machine, means for feeding a container, means for guiding a sealing strip and tearing strip adjacent the path of movement of said container, means for pulling said sealing strip and tearing strip downwardly between adjacent containers, means for pressing said sealing and tearing strips against the side of the container, means for severing said strips and means for pressing the ends of the severed strips against the ends of the container.

11. In a container sealing machine, means for feeding a container, means for guiding a sealing strip and tearing strip adjacent the path of movement of said container, means for pulling said sealing strip and tearing strip downwardly between adjacent containers, means for slitting the sealing strip adjacent to and parallel to the edges of the tearing strip, means for pressing said sealing and tearing strips against the side of the container, means for severing said strips and means for pressing the ends of the severed strips against the ends of the container.

12. In a container sealing machine, means for feeding containers to be sealed, means for securing a sealing strip along one side of the container, means for pressing the ends of the strip against the ends of the container, a rotatable carrier, means for feeding the containers one at a time to said carrier, and means for pressing the ends of the strip against the container while the container is in the carrier.

13. In a container sealing machine, means for feeding containers to be sealed, means for securing a sealing strip along one side of the con-

tainer, means for pressing the ends of the strip against the ends of the container, a rotatable carrier, means for feeding the containers one at a time to said carrier, and means including a pair of pivoted arms for pressing the ends of the strip against the container while the container is in the carrier.

14. In a container sealing machine for sealing container closures to containers, means for feeding containers to be sealed, means for applying and securing a strip along one side and the ends of the container over the junction of the container and closure, means for applying and securing another strip to the other side and ends of the container over the junction of the container and closure, the ends of the second strip overlapping the ends of the first strip, movable means for receiving the containers from the container feeding means, and means for pressing the ends of the outer sealing strip against the ends of the containers while the containers are positioned in the movable means.

15. Means for sealing closures to containers comprising means for feeding the containers and closures, means for applying a sealing strip to one side of the container bridging the adjacent portions of the container and closure, means for applying a second sealing strip to the other side of the container, bridging the adjacent portions of the container and closure, the ends of the sec-

ond strip overlapping the ends of the first strip, and means for positioning a tearing strip beneath said second sealing strip with the ends of the tearing strip extending beyond the ends of the second sealing strip.

16. In a container sealing machine for sealing closures to containers, means for feeding containers to be sealed, means for leading a sealing strip from a supply roll to the container and applying the strip to one side of the container and closure, means for severing the strip, means for securing the ends of the strip around the ends of the container and closure, means for leading a second sealing strip from a supply roll to the other side of the container and closure, means for applying and securing the second strip to said other side of the container and closure, means for severing the second strip and means for securing the ends of said second strip around the ends of the container and closure and over the ends of the first strip.

17. In a container sealing machine, means for feeding containers having hinged closures, means for securing a sealing strip along the side of the container having the hinges for the closure, means for slitting the strip intermediate the longitudinal edges thereof and in line with the hinges, and means for severing the strip between the ends of the slits.
